Patented Sept. 1, 1925.

1,551,530

UNITED STATES PATENT OFFICE.

DONALD R. ADAMS, OF ANCHORAGE, TERRITORY OF ALASKA.

PERPETUAL CALENDAR.

Application filed November 11, 1924. Serial No. 749,306.

To all whom it may concern:

Be it known that I, DONALD R. ADAMS, a citizen of the United States, residing at Anchorage, Territory of Alaska, have invented certain new and useful Improvements in a Perpetual Calendar, of which the following is a specification.

This invention relates to improvements in perpetual calendars and means for supporting the same on useful objects, such as pens, pencils, pen caps, and other objects of like nature.

A further object of this invention is the provision of improved means for maintaining perpetual calendars and the like in readily noticeable, but compact position on useful articles, such as pens, pencils, and the like.

A further object of this invention is the provision of improvements in means for maintaining articles, such as calendars and the like, in simple and compact relation on pens and pencils, or the like, without encumbering the pen or pencil part with objectionable structure.

A further object of this invention is the provision in improved calendar construction, such as set forth in my Patent #1,500,913, granted July 8, 1924.

Other objects and advantages of this invention will be apparent during the course of the following detailed description.

In the accompanying drawing, forming a part of this specification, and wherein similar reference characters designate corresponding parts throughout the several views,

Figure 1 is a side elevation of a fountain pen, showing the improved perpetual calendar and structure for maintaining the same in position thereon.

Figure 2 is a cross sectional view taken through the cap of the pen illustration in Figure 1, showing structural details of the same.

Figures 3 and 4 are fragmentary front elevations of the perpetual calendar structure embodied in the pen cap illustrated in Figures 1 and 2, showing respectively calendar months with 31 and 30 days therein.

Figure 5 is a cross sectional view taken substantially on the line 5—5 of Figure 2.

In the drawing, wherein for the purpose of illustration is shown only a preferred embodiment of this invention, the letter A

may generally designate a fountain pen, or other useful object, with which the improved perpetual calendar structure may be used, and which may embody the conventional body B and the cap C in which the improved structural features of the perpetual calendar are embodied.

The cap or member C preferably includes a substantially cylindrical shaped hollow supporting body 10, providing a passageway 11 therethrough which is open at the lower edge 12 of the body 10. The body upwardly thereof is reduced in thickness, providing the annular recess 13 inletting from the upper edge 14 of the body 10, which fixedly receives a reduced portion 15, which to all intents and purposes may be considered as a part of the body 10. This reduced portion 15 is preferably hollow and cylindrical in formation, and may be formed of metal such as aluminum; the lower end of the same resting in the groove 13 so that the inside surface defined by the passageway 16 through the reduced portion 15 lies flush with the passageway 11 through the body 10. The reduced portion 15 while the inside surface thereof lies flush with the inside surfaces of the passageway 11 is less in thickness than that of the body 10, so that the outer surface or circumference of the reduced portion 15 is disposed inwardly for a short distance from the outer circumference of the body 10 extended. Upwardly of the edge 14 of the body 10, the reduced portion 15 is provided with a circumferential groove of considerable width, adapted to receive an annular strip 20, of any approved material, such as paper, pyroxyline, or the like, so that the outer circumference of this strip 20 lies flush with the outer surface or circumference of the reduced portion 15. On this strip 20 is preferably delineated a plurality of sets of numerals arranged in the form of calendar months; these sets having 28, 29, 30 or 31 days therein, and preferably arranged somewhat in the form shown in detail in my Patent #1,500,913, although the numerals may be arranged different from that illustrated in this patent.

In the upper part of the reduced sleeve or portion 15, an annular flange 25 is provided, which annularly extend inwardly of the passageway 16, to restrict the same at the top of the reduced portion 15. This

upper portion 25 of the reduced portion 15 at the upper edge thereof is provided with an annular series of V-shaped teeth 28, of any approved number, which extend upwardly from the reduced sleeve 15 and not laterally outwardly thereof. The portion 15 within the upper opening defined by the annular portion 25 provides a screw threaded opening 29.

10 A hollow substantially cylindrical shaped sleeve 30 is provided as a part of the cap structure C, which is formed of the same material as the body 10, and which is adapted to be slipped over the reduced portion 15; the same having an opening 31 therethrough, preferably polygonal, to expose only one set of calendar numerals of the strip 20. In position on the reduced portion 15 the lower edge 33 of the sleeve 30 rests on the upper edge 14 of the body 10, and the outer circumference of the sleeve 30 lies substantially flush with the outer circumference of the body 10. On the exterior circumference of the sleeve 30, immediately above the opening 31, the letters S, M, T, W, T, F, S designate the days of the week, and which are arranged in co-operative relation with the columns of figures in the set of numerals which are exposed through the opening 31, in accordance with my invention which is set forth in Patent #1,500,913. In the upper portion thereof the sleeve 30 is preferably provided with an annular ring 38, preferably of aluminum or some analogous metal, which is affixed, as by riveting 39 to the sleeve 30, so that the upper portion thereof slightly projects upwardly of the top edge 41 of the sleeve 30. The lower marginal portion of this annular ring 38 is preferably provided with a plurality of V-shaped teeth 44, adapted to intermesh with the teeth 28 of the sleeve portion 25. The passageway 46 through the ring 38 is greater than the diameter of the screw threaded opening 29, and aligns therewith.

15 A clamping cap 50 is preferably provided as a part of the cap C, which is in the form of a screw, and preferably of some material such as hard rubber, porcelain, or in fact of any material desired. This clamping screw or cap 50 preferably includes a head portion 52 with a depending externally screw threaded shank 53 adapted for screw threaded engagement in the screw threaded opening 29 of the hollow reduced portion 15. The clamping screw 50 at the outer circumference of the head portion 52 provides a reduced depending flange 54 forming with the shank 53 an annular groove 56 adapted to receive the upwardly extending portion of the ring 38, so that the lower edge 57 of the flange 54 may engage the top edge 41 of the sleeve 30 when the clamping cap 50 is in position. It is preferred

that the head 52 of the screw 50 be externally knurled, to facilitate the removal thereof.

Referring to the operation of the invention, it is merely necessary to loosen the screw 50 so that the sleeve 30 may be slid upwardly on the reduced portion 15 of the body structure, and until the teeth 28 and 44 are out of meshing engagement. In this position the sleeve 30 may be laterally rotated to expose any set of numerals of a desired number of days according to the current month, and the set of numerals may be so placed that the first day of the month falls on any particular day of the week designated by the letters on the sleeve 30. When the desired calendar month having a predetermined number of days with the first day of the month falling on the particular day of the week has been selected, the sleeve 30 is lowered so that the teeth 44 thereof engage the teeth 28. This will lock the teeth against rotation on the body, and by rotating the screw 50 until the flange 54 thereof clamps on the top of the sleeve 30, the latter will be absolutely locked upon the body 10, to prevent rotation thereof, so that the current calendar month will be accurately exposed in the cap C.

From the foregoing discussion of this invention it is apparent that a novel perpetual calendar structure has been provided, which may be readily applicable to various structures, such as pens, pencils, and in fact any structure embodying the principles illustrated in the drawing.

Various changes in the shape, size, and arrangement of parts may be made to the form of the invention herein shown and described, without departing from the spirit of the invention or the scope of the claims.

I claim:

1. In a device of the class described the combination of a body portion having an upwardly extending reduced portion thereon with indicia thereabout, hollow sleeve means provided with an opening therethrough adapted to be slipped over the reduced portion of the supporting body so that certain indicia on the reduced portion is visible through said opening, interengaging teeth means carried by the sleeve and reduced portion, and clamping means adjustably carried by the reduced portion at its upper end adapted to engage the sleeve at its upper end to lock the same in a predetermined relation on said body.

2. In a structure of the class described the combination of a substantially cylindrical shaped body, a sleeve carried by said body and movable therealong, interengaging teeth means carried by said sleeve and said body, said body having a screw threaded opening therein, and a clamping screw including a screw threaded shank adapted for

adjustment in said screw threaded opening and including a head adapted to engage said sleeve for locking the latter on the body so that the teeth of the sleeve and body inter-
5 engage to hold the sleeve in a predetermined relation on said body.

3. In a device of the class described the combination of a substantially cylindrical shaped body, a reduced portion upwardly 10 extending from the body the outer circumference of which lies inwardly of the outer circumference of the body, said reduced portion having an annular groove inwardly of the exposed circumference thereof, an annular strip of material in said annular groove of the reduced portion having indicia thereon designating sets of calendar months of different numbers of days in each set, an inwardly extending flange upwardly in said 15 reduced portion providing an inner screw threaded opening and upwardly extending substantially V-shaped teeth arranged in an annular series on top of said reduced portion, a sleeve of hollow formation providing 20 a transverse opening therein, said sleeve adapted to be slipped over the reduced portion whereby the outer circumference of the sleeve lies flush with the outer circumference of said body with an edge of said sleeve in 25 engagement with an edge of said body, a ring shaped member upwardly carried in said sleeve providing a downwardly facing annular series of V-shaped teeth adapted to engage with the V-shaped teeth of said reduced portion whereby the opening in said 30 sleeve will expose a set of numerals of a predetermined number of days, said sleeve adjacent said opening having letters designating the days of the week in cooperative 35 relation with the numerals exposed through said opening, a cap screw including a reduced screw threaded shank adapted for engagement in the screw threaded opening of said reduced portion and having a laterally 40 extending flange adapted to clamp in engagement with said sleeve to hold the teeth of the latter in engagement with the teeth of the reduced portion.

4. In a structure of the class described the combination of a body having indicia arranged thereon designating a plurality of numerals arranged in the form of a calendar month, a hollow sleeve carried upon the body and movable thereabout and being provided 45 with an opening through which the numerals may be exposed, said sleeve having indicia arranged along an edge of said opening representative of the days of the week, said sleeve member when receiving the body 50 therein having a set of numerals displayed through the opening in the form of a calendar month with a predetermined number of days therein, interengaging teeth means carried by said sleeve and body adapted to hold the same in a predetermined relation

against displacement, said body having a screw threaded opening therein, and a clamping screw including a screw threaded shank for adjustment into said screw threaded opening and being provided with a head adapted to clamp the sleeve on the body with the interengaging teeth means in locked relation for holding the sleeve and body in a predetermined fixed relation. 70

5. In a device of the class described the combination of a body having a screw threaded opening at an end thereof, a sleeve adapted to be slipped over the body and having an open end through which the screw threaded opening is exposed, and an adjustable cap screw including a threaded shank for engaging into said screw threaded opening of the body and being provided with a head portion for clamping against said sleeve in order to hold the sleeve in a fixed 75 relation with respect to the body, said body having indicia thereon and said sleeve being provided with an opening therethrough for displaying said indicia according to the position which said screw holds the sleeve upon 80 said body.

6. In a device of the class described the combination of a body having teeth arranged about an upper edge thereof and being provided with a screw threaded opening inwardly of said teeth at its upper end, a hollow sleeve on the body provided with teeth adjacent the upper edge thereof adapted to intermesh with teeth of the body when the sleeve is positioned upon the body, said sleeve having an open end to expose said screw threaded opening, and a detachable screw member for the screw threaded opening including a portion adapted to extend 95 into abutment with the sleeve at its open end for clamping the sleeve on the body so that the teeth of the sleeve and body interengage to hold the body and sleeve in a predetermined fixed relation. 100

7. In a device of the class described the combination of a body having indicia exteriorly thereon, teeth rigidly carried by said body at its upper edge and facing upwardly, a hollow sleeve having a passageway adapted to receive said body, teeth rigidly carried by said hollow sleeve within the passageway facing downwardly therein whereby to interengage with the teeth of the body when the sleeve and body are in assembled position, said sleeve having an opening therein for exposing certain of the indicia of the body according to the position of the sleeve on the body, and means for clamping the body and sleeve so that the teeth interengage in a definite relation. 110

8. In a device of the class described the combination of a body having indicia thereon and being provided with upwardly extending teeth at the top margin thereof and having a screw threaded opening inwardly 115 120 125 130

of the area between said teeth, a hollow sleeve having an opening therein, said hollow sleeve being adapted to be slipped over the body to expose certain of the indicia of the body through its opening, said sleeve upwardly thereof being open and having an inwardly extending annular portion about said opening with downwardly facing teeth adapted to intermesh with the teeth of said body when the sleeve is in position upon said body, and a cap screw including a screw threaded shank adapted to be inserted through the open upper end of the sleeve into the screw threaded opening of said body, said cap screw including a laterally extending annular flange for clamping against the top edge of the sleeve, said screw upon adjustment being adapted to tightly clamp the sleeve against the body and upon opening adjustment permitting limited longitudinal movement of the sleeve on the body to disengage the teeth of the sleeve and body and permit rotation of the sleeve on the body for the purpose of altering the arrangement of indicia exposed through the first mentioned opening of said sleeve.

DONALD R. ADAMS.
